UNITED STATES PATENT OFFICE.

WILLIAM M. WILKIN, OF ERIE, PENNSYLVANIA.

SAW-SASH FOR RECIPROCATING-SAW MILLS.

SPECIFICATION forming part of Letters Patent No. 338,125, dated March 16, 1886.

Application filed October 20, 1885. Serial No. 180,416. (No model.)

To all whom it may concern:

Be it known that I, WILLIAM M. WILKIN, a citizen of the United States, residing at Erie, in the county of Erie and State of Pennsylvania, have invented certain new and useful Improvements in Saw-Sashes for Reciprocating-Saw Mills; and I do hereby declare the following to be a full, clear, and exact description of the invention, such as will enable others skilled in the art to which it appertains to make and use the same.

This invention relates to the construction of the saw-sash of reciprocating-saw mills; and it consists in forming the same of one piece of metal.

Heretofore the saw-sash of reciprocating-saw mills—such, for example, as gang-mills—have been formed of many parts bolted together.

My improvement in the construction thereof consists in forming the sash of one piece of metal, and thereby I produce a sash possessing the desired strength with much less metal, thus saving not only the metal, but also lightening the load on the motor which drives the mill.

My construction also is much cheaper, as it not only saves metal, but also much labor and many bolts and nuts.

Where the sash is made of parts bolted together the parts have to be planed and fitted together perfectly, holes drilled for the bolts, and the bolts and nuts provided. By making it of one piece of metal all this work is saved.

Where the sash is made of parts bolted together the constant jar incident to its operation will loosen the nuts on the bolts, and constant care is required to keep the sash in good order. This, too, is avoided when the sash is made of one piece of metal.

My device is illustrated in the accompanying drawing by a single figure, which is a perspective view.

B marks the whole frame. *b* is a vertical slot through the top girt of the frame, in which 45 the saw-buckles of the saws are received. *b'* is a groove in the lower girt, which affords engagement for the lower saw-buckles which hook into it. *b²* *b³* are the guide-ribs on the sides of the sash, and *b⁴* is the nodule-pin with 50 which the connecting-rod engages.

The whole sash, as shown, is formed at one operation of casting. The slot *b* in the upper girt is formed by a core, and the nodule-pin may be cast in a chill or not, as desired. The 55 guide-ribs *b²* *b³* and the groove *b'* are formed by the mold.

There is very little work required to finish the sash after it comes from the sand. The 60 guide-ribs *b²* *b³* have to be planed off. The top girt requires to be faced on top so as to give a square seat for the saw-buckles. The groove *b'* has to be faced so as to give the hooks of the lower saw-buckles a square seat, and the nodule-pin, if not cast in a chill, must be finished. 65 This is all the work that is required on the sash, and it is very much less than where the sash is made of parts.

What I claim as new is—

1. A gang-saw-mill saw-sash consisting of 70 vertical stiles and upper and lower girts with proper means for attaching the saws to said girts formed of one piece of metal, substantially as and for the purposes set forth.

2. A gang-saw-mill saw-sash having the slot 75 *b* vertically through its upper girt, the groove *b'* forming a catch along the top of its lower girt, guide-ribs *b²* *b³* on its sides, and the nodule-pin *b⁴*, as shown, formed of one piece of metal. 80

In testimony whereof I affix my signature in presence of two witnesses.

WILLIAM M. WILKIN.
